US0D1105018S

(12) **United States Design Patent** (10) Patent No.: **US D1,105,018 S**
(45) Date of Patent: ** Dec. 9, 2025

(54) **SHOWER HEAD**

(71) Applicant: **Lam Research Corporation**, Fremont, CA (US)

(72) Inventors: **Bin Luo**, Beaverton, OR (US); **Sean M Donnelly**, Portland, OR (US); **Eric Madsen**, Sherwood, OR (US); **Jeffrey Womack**, Lake Oswego, OR (US); **Keith Joseph Martin**, Tualatin, OR (US)

(73) Assignee: **LAM RESEARCH CORPORATION**, Fremont, CA (US)

(**) Term: **15 Years**

(21) Appl. No.: **29/928,490**

(22) Filed: **Feb. 12, 2024**

(57) **CLAIM**

The ornamental design for a shower head, as shown and described.

DESCRIPTION

FIG. 1 is a top perspective view of a shower head showing our new design.

FIG. 2 is a bottom perspective view of the shower head of FIG. 1.

FIG. 3 is a front view of the shower head of FIG. 1.

FIG. 4 is a back view of the shower head of FIG. 1.

FIG. 5 is a right side view of the shower head of FIG. 1.

FIG. 6 is a left side view of the shower head of FIG. 1.

FIG. 7 is a top view of the shower head of FIG. 1; and,

FIG. 8 is a bottom view of the shower head of FIG. 1.

The broken lines in the figures are directed to environment

and form no part of the claimed design.
